HEATING OF FLUIDS

Marion W. Barnes, Chicago, Ill., assignor to Universal Oil Products Company, Chicago, Ill., a corporation of Delaware

Application January 20, 1934, Serial No. 707,535

3 Claims. (Cl. 122—356)

This invention particularly refers to improvements in the heating of fluids which is particularly well adapted to subjecting hydrocarbon oils to the high temperatures required for their pyrolytic conversion, although it is not limited to such use and may be employed to advantage in the heating of liquid, vapors and gases generally as well as mixtures of the same.

I have previously disclosed an improved type of furnace for the heating of fluids having two independently fired combustion zones each containing fluid conduits supplied predominantly with radiant heat, the heating conditions in each being independently controlled, and having a centrally located fluid heating zone separated from each combustion zone by a bridge wall and containing a fluid conduit around which the combustion gases from both combustion zones pass in a downward direction thereby supplying fluid heat thereto. The present invention embodies improvements to this general type of furnace structure, comprising locating the fluid heating bank adjacent the roof of the furnace above and at substantially right angles to the source of heat. I have found that this arrangement augments the natural draft conditions in the furnace, since the movement of the gases through the furnace due to the stack draft is in harmony with the natural tendency of the heated gases to rise. This largely eliminates eddy currents and the back-wash of gases along the fluid conduit and results in a more definite separation of radiant and convection heat than in any other furnace of the so-called "open radiant" type. This eliminates any dangerous and excessive superimposing of convection and radiant heat in the fluid conduits located within the combustion zones and permits better control of the heating conditions in each of the three heating zones. The improved form of furnace of the present invention eliminates expensive bridge wall construction, underground flues and considerably decreases the height of the main furnace structure.

The features of the present invention and their advantages will be more apparent with reference to the accompanying diagrammatic drawing and the following description thereof, the single figure of the drawing being a cross-sectional elevation of one specific form of furnace embodied by the present invention.

Referring to the drawing, the main furnace structure comprises end walls 1 and 1', a roof 2, a floor 3 and side walls which do not appear in the particular view shown. A centrally located fluid heating zone 4 extending through the roof

of the furnace is separated from combustion zones 5 and 6 by relatively short suspended walls 7 and 7' whereby the main furnace structure is divided into three separate heating zones 4, 5 and 6.

A plurality of suitable firing tunnels such as indicated at 8 are provided at each end of the furnace and a combustible fuel-air-mixture of any suitable form is supplied by means of burners 9 through firing compartment 10 of tunnels 10 8 to each of the combustion zones 5 and 6. Any desired portion of the air required for combustion as well as any desired quantity of excess air may be supplied to each of the combustion zones through ducts 11 and 11' of firing tunnels 8 15 which, in the case illustrated, are located respectively above and beneath firing compartments 10. Excess air may also be admitted, when desired, through firing tunnels 10.

It will be noted that in the furnace structure here illustrated there are no obstructions in the direct path of flow of the combustion gases from firing tunnels 8 to the fluid heating zone 4; walls 7 and 7' preferably extending only a relatively short distance below roof 2 sufficient to prevent the sweep of hot combustion gases along the roof of the furnace to fluid heating zone 4 but not sufficient to obstruct or retard the free flow of gases through the combustion zones into the fluid heating zone. It will also be noted that firing tunnels 8 are elevated, in the preferred embodiment here illustrated, sufficiently to prevent the sweep of hot combustion gases along the floor of the furnace. In this manner predominantly radiant heat is imparted to the fluid conduits along the roof and floor of the combustion zones with a minimum of superimposed convection heat. The general direction of flow of the hot combustion gases from firing tunnels 10 through combustion zones 5 and 6 to fluid heating zone 4 is indicated by the arrows in the figure. The hot combustion gases from both combustion zones commingle within and beneath fluid heating zone 4 and pass upward therethrough to a suitable flue 12 leading to a stack, not shown.

A fluid conduit 13 comprising, in the case illustrated, a single horizontal row of horizontally disposed tubes 14 is located adjacent the floor of combustion zone 5 and a similar fluid conduit 15, also comprising, in the case illustrated, a single horizontal row of horizontally disposed tubes 14, is located adjacent the floor of combustion zone 6. Another fluid conduit 16 comprising, in the case illustrated, a single horizontal row of horizontally disposed tubes 14 is located adjacent the roof of

combustion zone 5 and a similar fluid conduit 17 also comprising, in the case illustrated, a single horizontal row of horizontally disposed tubes 14 is located adjacent the roof of combustion zone 6. 5 Another fluid conduit 18 comprising a plurality of horizontally parallel rows of horizontally disposed tubes 14 is located within fluid heating zone 4. Although not illustrated in the drawing, the tubes 14 of each of the banks 13, 15, 16, 17 10 and 18 extend across the entire width of the various heating zones and terminate in suitable headers or return bends, preferably located outside the heated zone. It will be understood that two or more rows of tubes may, when desired, be 15 employed in any or all of the fluid conduits 13, 15, 16 and 17 although preferably when more than a single row is utilized the tubes are so spaced that the projected surface of each is exposed to direct radiation from the flames and 20 hot combustion gases in combustion zones 5 and 6. It is also within the scope of the invention, when desired, to eliminate the portions of fluid conduits 13 and 15 located beneath fluid heating zone 4 and indicated in the drawing at 13' and 15', 25 respectively. Elimination of these tubes will serve to substantially increase the heat imparted to tube bank 18 and particularly the lower 2 or 3 rows of this bank.

As indicated by the arrows on the drawing, the 30 oil or other fluid to be heated enters the upper row of tubes in tube bank 18, flowing in series through adjacent tubes in the same row and through the adjacent rows of tubes in a general direction counter-current to the direction of flow 35 of combustion gases through this zone of the furnace, emerging from the lower row of tubes in bank 18 and entering the end tube of roof bank 17 adjacent tube bank 18, flowing in series through adjacent tubes in bank 17 in a general 40 direction counter-current to the direction of firing, emerging from the end tube of bank 17 adjacent the end wall of the furnace and entering the last tube at the same end of floor bank 15, flowing in series through adjacent tubes in 45 this bank in a general direction concurrent to the direction of firing, flowing then in series through adjacent tubes in floor bank 13 in a general direction countercurrent to the direction of firing, emerging from the end tube of bank 13 adjacent the other end wall of the furnace and entering 50 the last tube at the same end of roof bank 16, flowing in series through adjacent tubes in this bank in a general direction concurrent to the direction of firing and being discharged from the end tube of bank 16 adjacent bank 18 and from 55 the furnace.

This general type of flow wherein the same stream of fluid passes through the fluid conduits in one combustion zone of the furnace and then 60 through the fluid conduits in the other combus-

tion zone of the furnace will be found particularly advantageous whenever it is desirable to maintain different heating conditions in the latter stages of heating as compared to those employed in the previous heating stages. As an example of its practical application this flow may be employed for the reforming of light distillates, such as those containing a substantial proportion of materials within the boiling range of motor fuel, wherein it is desirable to first heat the distillate to the desired conversion temperature and then to maintain the stream of heated distillate at or near the maximum temperature previously attained for a predetermined time.

I claim as my invention:

1. In combination with a furnace having end walls, a roof and a floor, means forming a convection heating zone extending upwardly from the central portion of the furnace roof, heating tubes in said zone, additional heating tubes in the end portions of the furnace proper on the opposite sides of said zone, means for firing the furnace above the floor in opposite directions through the end walls substantially horizontally toward the central portion of the furnace, means for removing combustion gases from the convection heating zone, and means for passing fluid serially through the tubes in said zone and in the furnace proper on the opposite sides of said zone.

2. In combination with a furnace having end walls, a roof and a floor, means for firing the furnace through the end walls and above the floor in opposite, substantially horizontal directions toward the central portion of the furnace, means forming an outlet duct for combustion gases through the central portion of the furnace roof, heating tubes in said duct, additional heating tubes in the furnace proper on both sides of said duct, and disposed substantially at right angles to the direction of firing, and means for passing fluid serially through the first-mentioned tubes and said additional tubes.

3. In combination with a furnace having end walls, a roof and a floor, means for firing the furnace through the end walls and above the floor in opposite, substantially horizontal directions toward the central portion of the furnace, means forming an outlet duct for combustion gases through the central portion of the furnace roof, heating tubes in said duct, roof tubes in the upper portion of the furnace on the opposite sides of said duct, additional heating tubes in the end portions of the furnace adjacent the furnace floor, said roof tubes and additional tubes being disposed substantially at right angles to the direction of firing, and means for passing fluid serially through the first-mentioned tubes, the roof tubes and said additional tubes.
